UNITED STATES PATENT OFFICE.

BENJAMIN M. GRIFFITH, OF PITTSBURGH, PENNSYLVANIA, ASSIGNOR TO NATIONAL CASKET COMPANY, OF PITTSBURGH, PENNSYLVANIA, A CORPORATION OF NEW YORK.

DIPPING MACHINE.

Application filed December 2, 1921. Serial No. 519,424.

To all whom it may concern:

Be it known that I, BENJAMIN M. GRIFFITH, a citizen of the United States, residing at Pittsburgh, in the county of Allegheny and State of Pennsylvania, have invented a new and useful Improvement in Dipping Machines, of which the following is a full, clear, and exact description.

The present invention relates to dipping machines, and more particularly to dipping machines in which the articles to be dipped are carried continuously by a conveyor and immersed thereby in a dipping tank. The articles are held by holders mounted on the conveyors and arranged so that as the conveyor passes the tank the holder turns to immerse the article in the dipping tank and then withdraw it. The articles after being dipped are dried.

In the drawings which illustrate the preferred embodiment of the invention,—

Figure 1 is a plan view of the dipping apparatus, a horizontal section being shown through the casing which surrounds it;

Figure 2 is a perspective view of the dipping tank;

Figure 3 is a detail view showing the track at the dipping station;

Figure 4 is a side elevation, taken partly in section along the line IV—IV of Figure 3, showing one of the holders;

Figure 5 is a detail view of part of a holder;

Figure 6 is a section along the line VI—VI of Figure 3;

Figure 7 is a section along the line VII—VII of Figure 3; and

Figure 8 is a section along the line VIII—VIII of Figure 4.

Referring to the illustrated embodiment of the invention, the dipping mechanism comprises an endless chain 1 having a plurality of holders 2 carried thereby for holding the articles to be dipped, in the illustrated case such articles being hollow metal rods 3. The chain carries the articles continuously past a dipping tank 4 which contains the coating material, such as lacquer. As the chain passes the tank, the holders operate to turn the rods 3 from vertical to horizontal position, at the same time lowering them into the dipping tank 4, and then raising them. The mechanism is enclosed in a casing 5 which is heated, preferably by

steam coils (not shown) in order to dry the 55 coated articles.

The casing 5 has an opening 6 through which the articles may be placed upon the holders and removed by the workman. It has a door 7 through which access may be 60 had to the dipping tank 4. A partition 8 extending longitudinally along the casing divides it into two parts. The chain 1 is carried on sprocket wheels 9 at the end of the partition 8. The chain is continuously 65 driven by a power driven shaft 10 geared to one of the sprocket wheels 9. Extending around the path of travel of the chain, is a track 11 which is made of angle iron for substantially its entire length except at the 70 dipping station. At the dipping station this track is cut away, as indicated at 12 in Figures 3 and 7, to allow the holders to turn and dip the articles in the dipping tank.

Each holder, which is indicated generally 75 by the reference numeral 2, comprises an upstanding pin 13, which enters the interior of one of the hollow rods 3. The pin 13 is made of two plates of metal 13^a and 13^b welded together. The pin 13 fits in a socket 80

30. The excess lacquer in the hollow rods 3 is thereby permitted to run past the pin 13 through the socket and escape through the unobstructed socket 30. The pin 13 is carried on a jointed arm 14, comprising the two 85

parts 15 and 16 which are pivoted at 17. As shown in the drawings, every fourth link of the chain is provided with an integral upstanding pin 18, over which fits the portion 16 of the holder arm. The connection between the part 16 and the pin 18 is a rigid connection. During the major portion of the travel of the conveyor chain, the arm 14 is held straight in the full line position shown in Figure 4. When the cut away portion 12 of the track is reached, however, the section 15 of the arm is allowed to drop about the pivot pin 17. This turns the bar 3 to be coated from the vertical to a horizontal position, and at the same time drops 90

it into the dipping tank 4. As can readily be seen, the part 15 pivoting around the pin 17 causes the end which holds the rod to swing down below the point 17 by the length of the piece 15. A stop 19 on the part 16 95 limits the downward movement of the part 15, so that it does not swing beyond the vertical. A roller 20 is carried on the shaft of 100

105

the part 15 so that it rides easily along the track.

The track 11 for the greater part of its distance consists in an angle iron, as shown at the two ends of Figure 3. At the dipping station, the track is formed by a plate 40, having an upcurved front edge 41, along which the rollers 20 travel. This curved edge is cut away at 12, as shown in Figures 3, 6 and 7, to allow the rod-holding arms to turn and immerse the rods in the dipping tank. An upstanding flange 42 is secured to the plate 40, and serves to support the part 16 of the holder arm when the pivoted part 15 falls to immerse the rods in the tank.

The operation of the device is as follows, described with particular reference to coating hollow metal bars as shown in the drawing, with lacquer. These bars are used in the casket industry. They are first washed and then placed by the workman through the door 6 and on the pins 13. The chain is continuously traveling and carries the prepared rods to the left, as shown at the top of Figure 1. The rods are thoroughly dried by the heat in the casing 7 before they arrive at the dipping station. When a holder arrives at the cut-away portion 12 of the track, the roller 20 rides down into such cut-away portion, turning the bar around an axis parallel to the travel of the chain, and at the same time lowering it so that the bar is immersed in the lacquer tank 14. It is immediately withdrawn by the travel of the roller 20 out of the depression 12 and up on to the travel. The bars then travel along the extension 21 of the dipping tank into which they dip. The coating is subjected to the drying heat in the casing, so that by the time the bars again reach the opening 6, they are thoroughly dried. They are then removed from the holders by the workman.

It is to be understood that the present invention is not limited to its illustrated embodiment or limited to operation upon the specific articles herein shown, but that the invention may be otherwise embodied within the scope of the following claims.

I claim:

1. A machine for dipping articles, comprising a dipping tank, a conveyor, holders on the conveyor for the article to be dipped, and means for turning the holders about an axis parallel to the travel of the conveyor to immerse the articles in the dipping tank, substantially as described.

2. A machine for dipping articles, comprising a dipping tank, a conveyor, a holder secured to the conveyor for holding the

articles to be dipped, said holder comprising a pivoted arm, and a track on which the pivoted arm rides having a cut-away portion at the dipping station whereby the arm is allowed to fall and immerse the articles in the dipping tank, substantially as described. 65

3. A machine for dipping articles, comprising a dipping tank, a conveyor, holders on the conveyor for the articles to be dipped, having pivoted arms, and means for turning the pivoted arms of the holders at the dipping station to immerse the articles in the dipping tank, substantially as described. 70

4. A machine for dipping articles, comprising a dipping tank, a conveyor, holders on the conveyor for the articles to be dipped, comprising arms for holding at their ends the articles to be dipped and pivoted so as to both turn and lower the articles to be dipped, and means at the dipping station for causing the pivoted arms to turn and thereby dip the articles in the dipping tank, substantially as described. 75

5. A machine for dipping articles, comprising a dipping tank, an endless chain, holders for the articles to be dipped, each holder comprising a part fixed to the chain and a second part pivoted thereto and carrying at its end the article to be dipped, a track extending along the path of the chain and serving to support the pivoted arms except at the dipping station, said track being cut away at the dipping station to allow the arms to fall and immerse the articles in the dipping tank, substantially as described. 80

6. A machine for dipping rods, comprising a dipping tank, a conveyor, holders on the conveyor, each holder comprising a part fixed to the conveyor and an arm pivoted thereto and arranged to normally hold the rod in a vertical position, and means at the dipping station for causing the pivoted part of the holder to drop and to turn the rod into a horizontal position and immerse it in the dipping tank, and thereafter to withdraw it from the dipping tank and turn it to an upright position, substantially as described. 95

7. A machine for dipping articles, comprising a dipping tank, a conveyor chain, holders on the chain for the articles to be dipped, and means for turning the holders at the dipping station so as to immerse the articles in the dipping tank, substantially as described. 100

In testimony whereof I have hereunto set my hand. 105

BENJAMIN M. GRIFFITH.
